(57) **CLAIM**

The ornamental design for a storage rack, as shown and described herein.

DESCRIPTION

FIG. 1 Is a perspective view of my storage rack;

FIG. 2 Is a front view thereof;

FIG. 3 Is a rear view thereof;

FIG. 4 Is a right side view thereof;

FIG. 5 Is a left side view thereof;

FIG. 6 Is a bottom view thereof; and,

FIG. 7 Is a top view thereof.

The broken lines shown in the drawings form no part of the claimed design. In FIGS. 1, 4 and 5 the slots are not claimed, and in FIGS. 1-7 the boundary of the shelves are not claimed.
